United States Patent Office

Des. 214,552
Patented July 1, 1969

214,552

JUG

David G. Hills, Collinsville, Conn., assignor to Monsanto
Company, St. Louis, Mo., a corporation of Delaware

Filed Oct. 6, 1967, Ser. No. 8,901

Term of patent 14 years

Int. Cl. D9—01

U.S. Cl. D9—51

FIG. I

FIG. II

FIG. III

FIG. IV

FIG. I is a perspective view of a jug, showing my new design;

FIG. II is a side elevational view thereof;

FIG. III is an enlarged top plan view thereof;

FIG. IV is an enlarged sectional view taken along the line IV-IV of FIG. II.

I claim:

The ornamental design for a jug, as shown.
